(57) **CLAIM**

The ornamental design for a bottle, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front-side view of a bottle;

FIG. 2 is a side view of the bottle of FIG. 1; and,

FIG. 3 is a top-side plan view of the bottle of FIG. 1.

The portions of the drawings illustrated in dashed lines, if any, depict portions of the article that form no part of the claimed design. The portions of the drawings illustrated in dash-dot-dash lines, if any, indicate boundaries that form no part of the claimed design.

1 Claim, 3 Drawing Sheets
(3 of 3 Drawing Sheet(s) Filed in Color)
